STARTING AND STOPPING MECHANISM

Fred C. Eastman, Beverly, Mass., assignor to
 United Shoe Machinery Corporation, Paterson,
 N. J., a corporation of New Jersey

Application February 20, 1930, Serial No. 430,049

20 Claims. (Cl. 192—148)

This invention relates to starting and stopping mechanisms and is illustrated herein as embodied in a mechanism developed for use in a fastening inserting machine of the type shown in copending application Serial No. 430,071, filed Feb. 20, 1930, in the name of Fred N. LaChapelle and Fred C. Eastman, and since issued as Letters Patent No. 1,918,274, dated July 18, 1933.

It is an object of the invention to provide 10 an improved clutch of the rotating key type which is suitable for use in machines of this general type and which can be used also in machines of other types.

With the above object in view, a feature of 15 the invention consists of mechanism adapted to rotate the key, in a clutch of the rotating key type, into clutch engaging position, which mechanism, after movement of a controlling member, is driven by power from a moving member.

20 This member is driven while the clutch is disengaged and it may be driven continuously. For example and as herein illustrated, it is driven by movement of a continuously rotating part of the clutch, i. e., by the driving member of the 25 clutch. The key is rotated to engage teeth on the driving member and, because this member itself also causes the rotation of the key, the key is rotated in timed relation to the movement of the teeth.

30 Another feature of the invention consists, in a clutch having power driven or operated means for rotating the key into clutch engaging position, of power driven or operated means for throwing the key into disengaged position, the power for this purpose being supplied preferably 35 by the bodily movement of the key as it is carried, with its associated parts, around with the driving shaft.

40 A further feature of the invention consists, in combination with a clutch of the above type, of means for adjusting the position of the part that operates to throw the clutch out of engagement so that it will operate at the proper time in the cycle of the machine driven thereby, to 45 allow it to drift to a stop at the completion of a single revolution.

50 Another feature consists, in a clutch having a power operated member for rotating a clutch key into clutch engaging position and means for disengaging it, of a controlling member for rendering the power operated means effective, said controlling member being constructed and arranged to prevent re-engagement of the clutch 55 until after the controlling member has been

moved to neutral position and repositioned in starting position.

Another feature of the invention consists in a novel arrangement of parts for rotating the key comprising a longitudinally yielding plunger located in a bore in the key, a radial arm on the plunger by which the key may be rotated and means, preferably power operated, by which the arm may be turned to bring the key into clutch engaging position. 60

65 A further feature consists, in the combination with an arm for rotating the key into clutch engaging position, of another arm, connected to the key, by which the key may be rotated to disengaged position when the second arm is acted upon, during rotation of the clutch, by a fixed member.

70 The features of the invention outlined above, as well as the further features hereinafter described and claimed, will be understood when 75 they are considered in connection with the accompanying drawing, in which,

Fig. 1 is a side elevation, partly in section, showing the head of a fastening inserting machine of the type shown in the copending application referred to and illustrates features of the 80 clutch mechanism of the present invention;

Fig. 2 is a front view, on an enlarged scale, of the clutch mechanism with certain parts thereof shown in section along the line II—II of Fig. 85 1 and looking in the direction of the arrows;

Fig. 3 is a section of the clutch taken along the line III—III of Fig. 2 and looking in the direction of the arrows; and

Fig. 4 is a section taken on the line IV—IV of Fig. 2 and looking in the direction of the arrows. 90

The mechanism of the fastening inserting machine is mounted upon a swinging frame or head 10, which is pivotally mounted on the shaft 12. The head may be counterbalanced by a spring 14 95

which tends normally to lift the head away from the work or it may be counterbalanced by a suitable distribution of weight therein. A hand lever 16 is fixedly mounted on a shaft 18 pivoted in the head of the machine. A torsion spring 19, 100 on the shaft 18, tends to lift the hand lever 16. The hand lever 16 is used to swing the head into operative relation with the work 20 which, as illustrated, comprises a shoe, the forward portion of which is supported by a toe rest 22, mounted in 105 a suitable holder 24, supported by the base of the fastening inserting machine. By pulling forwardly and downwardly upon the hand lever 16, against the force of the torsion spring 19, the head is carried into said operative position but 110

without, in the meantime, operating the clutch controlling mechanism which is also controlled by the same hand lever 16.

The shaft 18 also carries another lever 26 fixedly mounted thereon, and this lever 26 is connected by means of a connecting rod 28 to another lever 30. The lever 30 performs three functions, i. e., it serves to lock the head in work operating position, it is a portion of a safety mechanism by which operation of the clutch is prevented until the head is in operative position, and it carries a controlling member 32, pivotally mounted thereon, by which the clutch is started to operate the fastening inserting mechanism. The other portion of the safety mechanism referred to consists of a fixed cam 34 having a face 36 concentric with the shaft 12 and a radial face 38. As the head 10 of the machine is brought forward by the forward and downward pressure of the handle 16, the end of the lever 30 rides upon the concentric cam face 36 which maintains the controlling member 32 out of engagement with the clutch. The cam face 36 also acts as an abutment to prevent the handle from moving relative to the head 10, so that the handle is effective to bring the head into operative position. When the head reaches operative position, the end of the lever 30 drops off the concentric face 36 of the cam and reaches a position of clearance just in front of the radial face 38.

The clutch is then engaged and the machine started in a manner hereinafter to be described (in the direction indicated by the arrows in the various figures) and the lever 30 is then given a slight downward motion to take up the clearance between its lower end and the radial face 38 and to furnish pressure to clamp the head 10 in operative position. This movement and clamping pressure is obtained because the lever 30 is pivotally mounted upon a stud 39 on a cam lever 40 which lever is pivoted at 41 on the head 10 of the machine. The cam lever 40 carries a cam roll 42 which engages a cam 44 driven by the machine and shown in dotted lines in Fig. 1. A rise in the cam 44 lifts the cam roll 42 on the lever 40 and causes a depression and downward pressure of the upper end of the lever 40 upon which the lever 30 is mounted. The upper arm of the lever 40 and the lower arm of the lever 30 may be considered as a toggle having its upper end pivot at 41, its middle pivot at 39 and its lower end pivot or abutment on the radial face 38 of the fixed cam 34. As the pivot 39 moves down, it tends to force the pivot 41 away from the fixed abutment or face 38, causing a tendency for the pivot 41 to move in a clockwise direction, in Fig. 1, about the shaft 12. As the pivot 41 is mounted in the head 10, the head also has a like tendency to move which causes its outer end, carrying the fastening inserting mechanism, to move about the shaft 12 to clamp the work. The lever 40 has hereinbefore been considered as a single lever but it is actually made of two parts, which may be adjusted relatively to each other by means of an adjusting screw 46 so that the clamping pressure may be adjusted by suitably adjusting this screw.

As the end of the lever 30 drops off the concentric portion 36 of the cam (as previously described) the downward movement of the controlling member 32, mounted thereon, operates to engage the clutch and start the machine to cause movement of the cam 44 and the operation of the fastening inserting mechanism. The engagement of the clutch is effected, in a manner

to be described hereinafter, by a bevel or wedge portion 48 with which the lower end of the controlling member 32 is provided.

The fastening inserting mechanism and the above referred to safety devices, by which its operation is prevented until the said mechanism is in operating position, is not claimed herein but is claimed in the copending application referred to above.

The clutch mechanism which is claimed herein will now be described. The machine is operated from a continuously driven gear 56 mounted to turn freely on the shaft 12. This gear is driven by a pinion 58 arranged to turn with the driving pulley 60 of the machine. Upon the gear 56 is mounted the driving member 62 of the clutch. The driving member 62 is provided with teeth 64 by which it drives, through the action of a rotatable key 66, the driven member 68 of the clutch, which driven member is keyed to the shaft 12 by which the machine is driven. The rotatable key 66 is mounted and arranged to rotate in a cylindrical aperture in the driven member 68, the axis of the aperture being parallel with the axis of the shaft 12. The key 66 is provided with a longitudinal bore in which is positioned a longitudinally yielding plunger 70 having a radial arm 72. As the plunger is moved in the bore, the arm 72 slides in a slot 74 in the rotatable key 66 and when the arm 72 and plunger are caused to rotate, such rotation of the arm 72 causes the key 66 to rotate also. The plunger is normally yieldingly positioned to the right in Fig. 2 by means of a compression spring 76 lying in an enlarged portion 78 of the longitudinal bore in the key. This spring 76 bears, at one end, against the end of the enlarged portion of the bore and, at the other end, on a collar 80 pinned to the outer end of the plunger. Another means for rotating the key 66 is provided, which consists of an arm 82, shown as integral with the rotatable key 66 and provided at its outer end with an offset cylindrical portion 84.

In order to cause engagement of the clutch, the arm 30 is moved as above-described, by downward movement of the handle 16 after the fastening inserting mechanism has been properly positioned, to carry the controlling member 32 toward the shaft 12. This movement causes the beveled portion 48 of the arm to engage the collar 80 and continued motion of the controlling member causes the yielding plunger 70 and its arm 72 to move to the left in Fig. 2 until the arm 72 is brought into the path of movement of a series of short pins 86 secured in and extending from the driving member 62. When one of these moving pins strikes the arm 72, the arm is rotated by the pin and this rotation of the arm rotates the key 66, through its contact with the side of the slot 74, and the end segment 88 of the key (shown in section in Fig. 3) is brought into the path of one of the teeth 64 of the driving member and soon contacts therewith so that the clutch is engaged and the gear 56 then revolves the shaft 12 and the mechanism connected thereto. These parts are constructed, arranged and timed so that, as shown in Fig. 4, the particular pin 86a, which is about to operate the clutch, will not strike the arm 72 until the preceding tooth 64a has cleared the segment 88. After it has so cleared, the pin 86a strikes the arm 72, causing it gradually to rotate as the member 62 is rotating until, by the time the tooth 64b is about to strike the segment 88, the key has rotated to bring this segment into full bearing contact with the tooth 64b. The driven

member 68 of the clutch is now engaged with the driving member 62 (through the rotating key 66) and the clutch is started, causing the collar 80 to pass out of contact with the controlling member 32. The arm 72 then moves clear of the pin 86 with which it has been engaged, and is then out of the path of movement of all such pins because of the action of the spring 76, but the rotatable key 66 still remains in clutch engaging position, due to the pressure of the tooth 64b thereon and to the fact that there is no force tending to move it.

In order to disconnect the clutch just before a complete revolution has been made so that the machine will drift to stopping position at the end of one revolution, an adjustable stop cam 90 located upon a circumferentially adjustable bushing 92 is provided. The bushing 92, after being adjusted to cause the stop cam 90 to operate at the desired point, is clamped in adjusted position by a clamp screw 94. As shown in Fig. 4, the cylindrical portion 84 of the arm 82 of the rotatable key 66 strikes the stop cam 90 and rotates the key 66 gradually into non-engaging position so that the teeth 64 of the driving member will pass beneath the segment 88. The rotatable key is maintained in this position by the friction of the arm 72 against the face of the driven member 68, the friction being produced by the spring 76. The drift of the machine carries the cylindrical projection 84 sufficiently beyond the stop cam 90 so that the key may be rotated for the next revolution when the arm 72 is again positioned in the path of the pins 86.

As the machine is stopping, the collar 80 is in the path of the controlling member 32 and this member is pivotally mounted on the lever 30 so that it swings as the collar 80 strikes its side, and the clutch, therefore, cannot be reengaged until after the lever 30 is lifted to normal or neutral position to bring the controlling member 32 out of contact with the collar 80, after which the controlling member 32 swings back by gravity into its normal position relatively to the lever 30, as shown in Fig. 1. This normal position is determined by a stop pin 96 on the controlling member 32, which pin comes in contact with a stop pin 98 positioned in the lever 30. The above mentioned lifting of the lever 30 takes place after the cam 42 has relieved the pressure of the lever 30 on the radial cam surface 38. When this pressure is relieved and the hand lever 16 is released, the torsion spring 19, acting through the shaft 18, the lever 26 and connection 28, lifts the lever 30 free from the cam 34 and the head 10 is then returned to inoperative position by the counter-balancing spring 14.

Having described my invention, what I claim as new and desire to secure by Letters Patent of the United States is:

1. A starting and stopping mechanism having, in combination, a driving member, a driven member, a rotatable key, means by which the key may be rotated, and means on the driving member for causing said first-mentioned means to rotate the key into clutch engaging position.

2. A starting and stopping mechanism having, in combination, a driving member, a driven member, a rotatable key, means by which the key may be rotated, means on the driving member for causing said first-mentioned means to rotate the key into clutch engaging position, and means to move the key into disengaged position.

3. A starting and stopping mechanism having, in combination, a driving member, a driven mem-

ber, a rotatable key, means by which the key may be rotated, means on the driving member for causing said first-mentioned means to rotate the key into clutch engaging position, an adjustable member to move the key into disengaged position, and means for securing said adjustable member in fixed position to effect disengagement at a predetermined point in the revolution of the driven member.

4. A starting and stopping mechanism having, in combination, a driving member, a driven member, a rotatable key, a plurality of arms by which the key may be rotated, a projection on the driving member for engaging one of said arms and rotating the key into clutch engaging position and a fixed member for engaging another of said arms and rotating the key into disengaged position.

5. A starting and stopping mechanism having, in combination, a driving member, a driven member, a rotatable key in the driven member, an arm by which the key may be rotated, a controlling member for moving the arm longitudinally of the key, and a projection on the driving member for engaging the arm and rotating the key into clutch engaging position upon a longitudinal movement of the arm.

6. A starting and stopping mechanism having, in combination, a driving member, a driven member, a rotatable key in the driven member, an arm by which the key may be rotated, means for moving the arm longitudinally of the key, means on the driving member for engaging the arm and rotating the key into clutch engaging position upon a longitudinal movement of the arm, and a fixed member to move the key into disengaged position at a definite point in the revolution of the driven member.

7. In a clutch mechanism, a driving clutch member, a driven clutch member, a clutch key rotatable to form a positive connection between said members and power driven means for rotating the key into clutch engaging position.

8. In a clutch mechanism, a driving clutch member, a driven clutch member, a clutch key rotatable to form a positive connection between said members, power driven means for rotating the key into clutch engaging position and power driven means for rotating the key into disengaged position.

9. In a clutch mechanism, a driving clutch member, a driven clutch member, a clutch key rotatable to form a positive connection between said members, means extending radially from the key, and power driven means constructed and arranged to contact with said first-mentioned means and rotate the key into clutch engaging position.

10. A rotatable clutch key having a longitudinal bore, a longitudinally yielding plunger in said bore, and a radial arm connected to said plunger by which the key may be rotated.

11. In a clutch mechanism, a rotatable clutch key having a longitudinal bore, a longitudinal yielding plunger in said bore, a radial arm connected to said plunger, and power operated means for moving said arm to rotate the key.

12. In a clutch mechanism, a rotatable clutch key having a longitudinal bore, a longitudinally yielding plunger in said bore, a radial arm connected to said plunger, a manually operated controlling member for moving the plunger with its arm longitudinally, and power operated means for moving said arm to rotate the key into clutch engaging position after longitudinal movement of

the plunger has brought the arm into the path of movement of said power operated means.

13. In a clutch mechanism, a rotatable clutch key, power operated means for rotating the key into clutch engaging position, a controlling member for rendering the power operated means effective to rotate the key into clutch engaging position, and means for disengaging the clutch, said controlling member being constructed and arranged to prevent re-engagement of the clutch until after it has been moved to neutral position and repositioned in starting position.

14. In a clutch mechanism, a rotatable clutch key having a longitudinal bore, a longitudinally yielding plunger in said bore, a radial arm connected to said plunger, a controlling member for moving the plunger with its arm longitudinally, power operated means for moving said arm to rotate the key into clutch engaging position after longitudinal movement of the plunger has brought the arm into the path of movement of said power means, and a pivotal mounting for said controlling member whereby, after it has been operated and the clutch started, it will be inoperative to move the plunger until said member is returned to neutral position and then repositioned to move the plunger.

15. In a clutch mechanism, a driving clutch member, a driven clutch member, a clutch key rotatable to form a positive connection between said members, continuously moving means, and means for connecting the continuously moving means with the key, to rotate the key into clutch engaging position.

16. In a clutch mechanism, a driving clutch member, a driven clutch member, a clutch key rotatable to form a positive connection between said members, a member moving while the clutch is disengaged, and mechanism for causing said member to move the clutch key into clutch engaging position.

17. In a clutch mechanism, a rotatable clutch key, a member moving while the clutch is disengaged, means for connecting said member with the key to rotate the key into clutch engaging position and then to disconnect the same with the key in said position, and means to rotate the key into disengaging position.

18. In a clutch mechanism, a rotatable clutch key, a member moving while the clutch is disengaged, means for connecting said member with the key to rotate the key into clutch engaging position and then to disconnect the same with the key in said position, and stationary means acting while the clutch is engaged, to rotate the key into disengaging position.

19. In a clutch mechanism, a driving clutch member having a tooth, a driven clutch member, a clutch key mounted in the driven clutch member and rotatable to form a positive driving connection with said tooth, a member movable with said tooth for rotating the key in timed relation to the movement of said tooth for the purpose of forming said driving connection, and means for temporarily connecting the key and the last-mentioned member to rotate the key for said purpose by the power of the driving clutch member.

20. In a clutch mechanism, a continuously rotating driving clutch member having a plurality of teeth, a driven clutch member, a clutch key mounted in the driven clutch member and rotatable to form a positive driving connection with any one of said teeth, a plurality of members each angularly spaced equally from a corresponding tooth and movable therewith for rotating said key in timed relation to the rotation of said teeth for the purpose of forming said driving connection, and means for temporarily connecting the key and any one of the last-mentioned members to rotate the key for said purpose by the power of the driving clutch member.
